UNITED STATES PATENT OFFICE.

SANDERS V. COCHRANE, OF HUTCHINSON, KANSAS.

THRASHING-MACHINE FEEDER.

Application filed May 31, 1921. Serial No. 473,721.

To all whom it may concern:

Be it known that I, SANDERS V. COCHRANE, a citizen of the United States, residing at Hutchinson, in the county of Reno and State of Kansas, have invented certain new and useful Improvements in Thrashing-Machine Feeders, of which the following is a specification.

This invention relates to improvements in feeding devices for use upon thrashing machines.

The primary object of the invention is the provision of a feeding device including the ordinary main conveyor, and novel lateral conveying means, for conveying unthreshed grain, or the like, to the thrashing machine in an even, uninterrupted flow.

A further object of the invention is the provision of a feeding device of the above described character, which will do away with clogging, or stopping of a feeder, incident to pitching or depositing of grain laterally thereon.

Specifically, the invention embodies adjustable lateral conveyors, upwardly mounted of the main conveyors, of a feeder, and feeder extension, and extending in substantial parallel alignment with said main conveyors, for movement in the same direction therewith.

Other objects and advantages will be apparent during the course of the following detailed description.

In the accompanying drawings, forming a part of this specification, wherein like reference characters designate corresponding parts throughout the several views.

Figure 1 is a side elevation of a feeder and feeder extension, embodying the improved lateral conveyors, operatively connected to a thrashing machine.

Figure 2 is a transverse cross sectional view taken on the line 2—2 of Figure 4.

Figure 3 is a fragmentary longitudinal cross sectional view, through a feeder and feeder extension taken on the line 3—3 of Figure 2.

Figure 4 is a sectional view similar to Figure 2, showing certain other details in side elevation, taken on the line 4—4 of Figure 2.

Figure 5 is a fragmentary side elevation partly in cross section of a feeder and its connection to a thrashing machine.

Figure 6 is a fragmentary transverse cross section, taken on the line 6—6 of Figure 4.

Figure 7 is a cross section taken on the line 7—7 of Figure 4.

In the drawings, wherein for the purpose of illustration is shown a preferred embodiment of my invention, the letter A designates a thrashing machine of any approved type, having the feeder device B, and feeder extension C connected thereto for operation. The feeder, and feeder extension, embodies a main conveyor D, and the lateral conveyor means E.

The thresher A may be of standard type, the same having a power shaft 10 mounted rearwardly thereof adjacent to the feeder B. A feeding shaft 11, having the grain engaging fingers or blades 12, staggered thereon, as in standard formation, is rotatably carried by the feeder B, and adapted for rotation, by a driving belt 13, connected to a suitable pulley 14 on the power shaft 10. A shaft 16, is rotatably carried by the feeder device B, adjacent the thrashing machine A, the same having suitable sprocket wheels 17 thereon for receiving the endless main conveyor 18. The opposite or lower ends of the main conveyor 18 is operably wound around suitable sprockets 19 on the sliding shaft 20; said shaft 20 being the lower shaft of the feeding device B. The main conveyor 18 is of ordinary construction, the same preferably comprising a plurality of pivotal links, or the same may comprise a belt; it being a requisite of the conveyor 18, that the same have upstanding article collecting slats 21, for positively conveying grain thereover.

The feeder B is preferably provided with the side guide portions 25, each of said guide portions 25 including a vertical longitudinal rail 26, and an upwardly diverging arm or guide rail 27, as in the ordinary feeder construction. Suitable sheet iron side walls 28, are provided upon each side of the feeder B adjacent the thrashing machine A, and for the purpose of connecting said feeder to the thrashing machine A. The side walls 28 converge inwardly at 29, for connection to the thrashing machine A, and for the purpose of guiding the unthreshed grain from the main conveyor D directly into engagement with the blades 12 of the feeding shaft 11. The lower shaft 20 of the feeder B is slidably carried at the lower end of the feeder B, by a device to be subsequently described.

The part of the main conveying means

D of feeder B, is supported between the vertical portion 26, of the side guides 25, in such manner that the uppermost run of the conveyor will ride upon the top of a 5 floor 31, which is mounted in any approved manner in the pocket structure, provided by the side guides 25.

Referring now to the feeder extension C, the same is provided with a running gear 10 35 of ordinary construction, including a wheel 36, rotatably mounted upon an axle 37, said axle being supported to the feeder extension C by brace members 38. The feeder extension C is formed similar to the 15 feeder B, and connected thereto by the support 35^a. The side guiding or supporting portions 39 each includes the substantially vertical portion 40, and the upwardly diverging or outwardly inclining rails 41. 20 By this construction, a pocket 42 is provided intermediate the side guides 39. The floor 43 is mounted in the feeder extension C, having the main conveyor 44 mounted thereover in endless conveying manner, by attachment 25 to an upper shaft 45, and lower sliding shaft 46. This conveyor 44 is of construction similar to the main conveyor 18 of the feeder B; the same comprising a plurality 30 of pivotal links, having the article engaging slats 47 thereon. Suitable standard sprockets 48, of course, are mounted upon the shafts 45 and 46 for rotating the conveyor 44.

The conveyor shaft 16 of the feeder B is 35 preferably driven by a belt 49, engaging about a suitable pulley on the feeding shaft 11. Thus, the shaft 16 will be directly driven by the power shaft 10 of the threshing machine A, for rotating the main conveyor 18 of the feeder B.

40 An outer pulley 50 is mounted upon the shaft 16, and the same is adapted for receiving a belt 51; the belt 51 extending forwardly toward the upper end of the feeder extension C, and engaging a pulley 52, keyed 45 or otherwise rigidly secured upon the shaft 45 of the feeder extension C. Thus, the shaft 16 being positively driven by the power shaft 10 of thresher A, will in turn 50 convey the power of the shaft 10 through the belt 51, and pulley 52, to the shaft 45, and rotating the main conveyor 44 of the feeder extension C.

Referring now to the lateral conveying means E; the feeder B, and feeder extension C, are provided with substantially similar lateral conveyors 55 and 56 respectively. In the case of the lateral conveyor 55 of the feeder B, the same preferably 55 comprises an endless belt 57, preferably of the link type, having the substantially U-shaped article engaging lugs 58 extending upwardly therefrom at spaced intervals. The purpose for which the lateral conveyors 55 and 56 have been provided has been set forth to some extent. They are located at

each side of the main conveying means D. The lateral conveyor 55 is mounted downwardly at the lower end of the feeder B by the brackets 59, said brackets 59 being bolted or otherwise rigidly secured to the outer 70 surface of the side guides 25. Suitable brackets 60 are likewise positioned exteriorly of the side guides 25 as spaced intervals throughout the length of said guides 25, and adapted for receiving the endless conveyor 75 chain 57, whereby the lugs 58 of said chain will be carried upwardly from a floor 61; said floor 61 being carried adjacent the top of each of the side guides 25, and for a considerable distance upwardly from the 80 floor space of the main conveyor 18.

The lateral conveyors 56 of the feeder extension C, each comprise an endless belt 62, including the substantially U-shaped lugs 63, similar in formation to the lugs 58 of feeder B. The conveyors 56 are carried outwardly of the side guide rails 39 of the feeder extension C, in such manner, that certain of the upwardly extending lugs 63 will ride upon the lateral floors 64; said 90 floor 64 being positioned upwardly of the outside surfaces of the guide rails 39. In this connection, certain of the upwardly extending lugs 63 project from the extreme top of the bevelled sides 41, as is clearly 95 shown in Figure 2 of the drawings. The endless conveyor 62 is supported downwardly upon the lower end of the feeder extension by suitable brackets 65, upon the outsides of the rails 39. Brackets 66 are provided upon the upper end of the feeder extension C, for upwardly receiving the chain or conveyor 62. Intermediate brackets 67, similar in construction to the brackets 60, are provided for medially supporting and 100 adjusting the conveyor element 62, to the outer sides of the guides 39. Thus, the brackets 65, 66, and 67, are the supporting means for the various sprockets, and elements, whereby the side conveyors 56 are 105 operably mounted on the feeder extension C.

The brackets 59 and 65, of the feeder and feeder extension B and C respectively, are preferably of cast metal, each including a vertical portion and an upwardly inclined plate portion 69 for attachment to the guide rails 25 and 39, as by the bolts 70 or the like. A web portion 71 is provided integral upon each of the plate portions 69 for reinforcement purposes. The brackets 59 and 65 are provided upwardly thereof with suitable stub shafts 72, projecting horizontally therefrom and rotatably receive the sprocket wheels 73, for projection outwardly from the feeder B, and feeder extension C. Any suitable means 74, such as a set screw or the like, can be provided for maintaining the stub shafts 72 bolted or rigid in the sleeve or housing 75^a, provided for reception of said stub shafts 72. The primary 110

function of the brackets 59 and 65 is the provision of a belt tightening means for adjusting the position of the shafts 20 and 46 of the feeder, and feeder extension respectively. To this end, suitable side flanges 75 have been provided outwardly upon the brackets 59 and 65, extending horizontally thereof, to provide suitable slots 76 for the reception of the plates 77 of shaft housings 78. The shaft housings 78 are in sleeve formation, each provided with a plate 77 integral therewith; said plate 77 being provided with suitable slots for the reception of a bolt 79.

In order to facilitate entrance of the shaft housings 78 in the brackets 59 and 65, slots or openings 80 are provided from the edges of said brackets. The sleeves 78, are adapted for rotatably receiving the shafts 20 and 46, having ends projecting therefrom, outwardly of the feeder, and feeding extension, for the reception of suitable sprocket wheels 81, keyed or rigidly secured thereto in any approved manner. In this position, the sprockets 73 and 81 lie in substantially vertical alignment for the reception of the endless chain 57 of the feeder B. The chain 62 of the feeder extension C need not be trained over sprocket 81 of shaft 46, as the same is driven from shaft 45, as will be subsequently set forth. By reason of this slideable arrangement of the shafts 20 and 46, the same can be moved longitudinally of the feeder and feeder extension respectively. The bolts 79 which are rigidly secured in the plates 77, project rearwardly of the brackets 59 and 65, and project from suitable apertures in detachable plates 83; said detachable plates having suitable recesses therein for engagement over projecting ends 84 of the brackets 59 and 65. The plates 83 are rigidly secured to each of the brackets 59 and 65 by bolts 85, engaging the projections 84. A clamping nut 86 is provided for engagement over the extending screw threaded end of each bolt 79, whereby upon adjustment of said nut 86, the bolt 79 will reciprocate or slide the sleeves 78, in each of the brackets, for adjusting the positions of the shafts 20 or 46.

The brackets 66 mounted upon the upper end of the feeder extension C are adapted for mounting exteriorly on the side rails 39. Each of the brackets 66 include a stub shaft 88 upwardly thereof, rotatably receiving a sprocket 89, for projection upwardly adjacent the top of the guide rails 39. The stub shafts 88 are clamped or otherwise suitably secured in housings 90, cast integral on the bracket 66. Lower sleeves or housings 91 are provided upon the brackets 66, for rotatably receiving the shaft 45. Each end of the shaft 45 projects outwardly from the housings 91 provided therefor, and has a sprocket wheel 92 keyed or otherwise se-

cured thereto, in substantially the same plane as the upper sprocket wheels 89. The intermediate adjustable brackets 60 and 67, of the feeder and feeder extension respectively, are of identical formation. They 70 each include a body plate 93, for attachments by bolts 94, or otherwise, to the exterior of the side rails of the feeder and feeder extension. The brackets 60 and 67, are each provided upwardly with a spacing sleeve 95, adapted for receiving a bolt 96, for securely attaching the upper end of each of the brackets to the inclined part of the guide rails. The brackets 60 and 67, are 75 provided upon their lower or bottom portions, with an apertured extension 97, having an arm 98 detachably clamped thereto by bolt means 99, for various adjustments. Each of the adjustable arms 98 are provided upon their upper ends 100 with suitable 80 stub shafts 101, adapted for rotatably receiving the sprocket wheels 102.

The endless conveyor belt 55 of the feeder B is thus wound about the upper and lower sprocket wheels 73, and 81, of the bracket 59, and engaging a plurality of the adjustable sprocket wheels 102, throughout the length of said feeder B. The lateral endless conveyors 55 of the feeder B extend 85 forwardly, and are returned upon one of the brackets 60, having the sprocket wheel 102 thereon. In driving the endless conveyor 55, the shaft 20 supplies power therefor, by reason of the sprocket wheel 81 being keyed to said shaft.

The endless conveyors 62 of the feeder extension C, engage over the sprocket wheels 89 and 92 of the brackets 66 and are maintained in tightened position by the intermediate adjustable sprocket wheels 102 of the brackets 67. Each endless conveyor 62 is merely attached to the bracket 65, by the uppermost sprocket wheel 73. In this manner, the driven shaft 45 will convey the necessary power to operate the lateral conveyors 62 of feeder extension C.

It is preferred that the outer protecting or guard boards 103, be vertically disposed to protect the lateral conveyor means E being maintained in position by the aforementioned bolts 96, clamped to the brackets 60 and 67.

Suitable spacing sleeves 104, are provided downwardly upon the brackets 60 and 67, and having a bolt 105 extending outwardly therefrom to receive a clamping nut 106, to outwardly engage the projecting boards 103. In this manner, the outside protectors 103 will prevent any accidental contact with the lateral conveying mechanism, since the same is securely enclosed intermediate the side guide rails of the feeder and feeder extension, and the side protecting means 103.

In operating, it is customary to pitch or load the grain over the sides of the feeder

or feeder extension. This sometimes results in a load of grain merely engaging the top of the side guide rails 25 and 39. Thus, the main conveyor D will not engage the same and move it lengthwise into the thrashing machine. However, with the improved lateral conveying means herein described, the load of grain so pitched upon the side rail will be engaged by the upwardly extending lugs 58 or 63, and since the lateral conveyors move synchronously with the main conveyor means D, the load of grain will be conveyed into the thrashing machine, independent of the position which the same assumes.

It is to be noted, that the floors 61 and 64, of the feeder and feeder extension respectively, are disposed downwardly intermediate the guide rails and protectors 103, to provide a groove longitudinally of the feeder, and feeder extension for hiding of the links of the lateral conveyors, leaving merely the article engaging lugs 58 and 63 projecting therefrom.

Various changes in the shape, size and arrangement of parts, may be made to the form of the invention herein shown and described, without departing from the spirit of the invention or the scope of the claims.

I claim:

1. A feeder, comprising in combination a supporting body, main conveying means therein, and adjustable auxiliary conveying means laterally of said main conveying means, and mounted upwardly thereof for movement in the same direction therewith.

2. A feeder, comprising in combination a supporting body including upwardly extending sides to provide a pocket, main conveying means operatively mounted downwardly in said pocket, and conveying means mounted upwardly of said sides outwardly of the pocket on each side of said main conveying means.

3. A thrashing machine feeding device, comprising in combination a feeder having side guide rails thereon to provide a pocket, main conveying means downwardly mounted in said pocket, and lateral conveying means detachably and adjustably mounted outwardly and upwardly of the main conveying means.

4. A thrashing machine feeding device, comprising in combination a feeder and feeder extension, having upwardly and outwardly converging side guide rails, main conveyor means mounted longitudinally of said feeder and feeding extension, and lateral endless conveyors mounted outwardly and upwardly of said main conveyor for cooperative movement therewith to forward a load of grain into a thrashing machine.

5. A thrashing machine feeder, comprising in combination a supporting body, guide rails on said supporting body, main con-

veyor means on said body operating between and longitudinally of the guide rails, brackets mounted exteriorly of said guide rails, sprockets rotatably carried by said brackets, and auxiliary endless conveyor belts laterally of said main conveyor means trained over said sprockets, and engaging a portion of said main conveying means for synchronous movement therewith.

6. A feeder, comprising in combination a supporting body, main conveying means in said supporting body, and lateral conveying means mounted longitudinally of said main conveying means including brackets, sprockets carried by certain of said brackets, adjustable sprockets carried by certain other of said brackets, and an endless conveyor belt engaging said sprockets and a portion of said main conveying means for synchronous movement longitudinally therewith.

7. A grain feeder comprising a supporting body having spaced side rails to provide a pocket, main conveyor means operating longitudinally of and in a plane at the bottom of said pocket provided by the side rails, and auxiliary conveyors operating laterally of the main conveyor and exteriorly of said side rails and pockets provided thereby, said auxiliary conveyors including lugs extending upwardly of the top surfaces of said side rails.

8. A grain feeder for thrashing machines comprising a supporting body having spaced side rails to provide a pocket and upwardly diverging from the bottom of said pocket, a relatively wide main conveyor operating longitudinally of and in a plane at the bottom of the pocket provided by the side rails, and auxiliary relatively narrow chain conveyors operating laterally of the main conveyor and exteriorly of the side rails of said supporting body and pocket, said chain conveyors having lugs extending outwardly therefrom which during operation of the auxiliary conveyors are adapted for extension upwardly of the top surfaces of said side rail, above the pocket provided thereby for cooperation with said main conveyor in delivering a load of grain to a thrashing machine.

9. A grain feeder comprising a main conveyor, housings extending longitudinally at the sides of said main conveyor open at their tops and providing facing rails at opposite sides of the main conveyor converging upwardly from the plane of the main conveyor, auxiliary conveyors operating longitudinally in said housings providing portions adapted for extension upwardly in the housings above the tops of said facing rails, and drive means for operating said main and auxiliary conveyors for cooperative transportation of material thereon.

10. In a device of the class described, the combination of a feeder including a support-

ing body, front and rear transverse shafts, and an endless main conveyor trained over said shafts; a feeder extension including a supporting body, front and rear transverse shafts, and an endless main conveyor trained over said front and rear transverse shafts of the feeder extension; a belt connecting the front shaft of the feeder with the front shaft of the feeder extension for cooperative movement of said main conveyors; auxiliary conveyors at the sides of the main conveyors of said feeder and feeder extension; and means connecting said auxiliary conveyors with the main conveyors for synchronous drive of the same.

11. A grain feeder comprising a supporting body including a floor, side rails connected longitudinally at the side edges of said floor and upwardly diverging therefrom to provide a pocket extending longitudinally above said floor and intermediate said side rails, brackets exteriorly carried by said side rails, and guard boards carried by said brackets in spaced relation outwardly of each of said side rails to provide housing compartments intermediate said guard boards and side rails at each side of

said supporting body extending longitudinally thereof; main conveying means carried by said supporting body including a shaft 30 transversely and rotatably carried forwardly of the supporting body, a shaft transversely carried at the rear of said supporting body in adjustable manner for parallel movement toward or away from said forwardly carried shaft, and an endless conveyor carried by said shafts operating in a plane at the bottom of the pocket provided by said side rails; and auxiliary conveying means carried in the compartments at each side of said 40 main conveyor intermediate the guard boards and side rails of said supporting body, including relatively narrow conveyors, and adjustable supporting wheels, said auxiliary conveyors being connected for operation with a transverse shaft of said main conveyor and having portions extending upwardly above the compartments in which they operate above the side rails of said supporting body for cooperation in moving 50 material longitudinally of the supporting body with said main conveyor.

SANDERS V. COCHRANE.
